UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

ANTENNA-CIRCUIT ARRANGEMENT.

Application filed August 19, 1921, Serial No. 493,666, and in France November 11, 1915.

(GRANTED UNDER THE PROVISIONS OF THE ACT OF MARCH 3, 1921, 41 STAT. L. 1313.)

Application filed in France November 11, 1915, patented June 15, 1920, under 502,633; France, December 8, 1915, patented March 10, 1921, under 22,826; France, Dec. 13, 1917, 5 patented April 26, 1921, under 23,128; Germany, June 22, 1920; England, July 7, 1920, patented September 15, 1921, under 147,462; England, July 7, 1920, patented November 7, 1921, under 164,009; Argentina, February 10 8, 1923, patented June 15, 1923, under 19,872; Argentina, February 8, 1923, patented July 14, 1923, under 20,332; Australia, November 5, 1921, patented November 6, 1922, under 4334/21; Canada, January 10, 15 1921; Belgium, June 22, 1920, patented June 22, 1920, under 288,250; Spain, June 6, 1920, patented August 30, 1920, under 74,217; Holland, June 24, 1920; India, October 24, 1921; Norway, June 30, 1920; Poland, 20 Aug. 8, 1920; Sweden, June 26, 1920; Czechoslovakia, July 10, 1920.

In circuit arrangements suggested in the past for supplying current to radio telegraphic antennæ with cathodic generators, 25 the antenna-ground circuit is influenced in accordance with the known methods either by induction or branch connections under the control of a local oscillatory circuit associated with the generator.

30 By connecting together the two circuits, antenna-ground and the oscillatory circuit, two wave lengths may be obtained in the antenna.

It is the object of the present invention to 35 eliminate the phenomena whereby two waves are sent out.

In accordance with the present invention the antenna circuit is connected directly into one of the circuits of the generator, whereby 40 a single oscillatory circuit will be obtained.

The drawings exemplify two circuit arrangements embodying the present invention.

Fig. 1 represents the well known circuit 45 arrangement of a cathodic generator. In this figure the generator is represented by D and a current source X is connected in a branch between the plate P and a filament F. The oscillatory circuit comprising the 50 inductance L, connected in series with one winding of a transformer T and the condenser C, is inserted into the above mentioned branch circuit. The secondary wind-

ing of the transformer is in a branch between the grid G and the filament. An 55 auxiliary source Y feeds the filament. The antenna-ground circuit, not shown in the figure, is arranged to be actuated by the oscillatory circuit LC either by induction or by shunting.

60 Fig. 2, in which the same reference characters indicate the same elements as above, shows one embodiment of the invention. The oscillatory circuit is open and the antenna A is connected to one of the terminals 65 of the condenser C. One end of the inductance is grounded.

In Fig. 3 there is illustrated a circuit arrangement in which tuning of the antenna circuit is effected by means of a variable inductance a portion of which is included in the antenna. In this circuit the vacuum tube D comprises a filament F heated by the current source Y, a grid G and a plate P. A current source X is connected in a branch 70 circuit between the plate P and the filament F. The inductance L forms part of the antenna circuit AH without the insertion of the capacity C of Fig. 1. Instead of using a transformer T, the grid G is connected to 75 a winding T' connected and coupled with the inductance L.

80 In order to change the length of the wave sent out, it is necessary in such a system to modify the number of turns in L. On the other hand, in order to obtain maximum power from the generator, it is also necessary to modify the number of turns in T' depending upon the length of the wave. When the number of turns in L is reduced, the 85 number of turns in T' must be increased and vice versa.

90 As shown in Fig. 3 this result may be obtained in response to a single operation. In this arrangement, waves of different lengths 95 are sent depending upon the position of the sliding contact K which divides the total inductance LT' in sections of the desired values.

100 Fig. 3 also shows a manipulator or interrupting key I for controlling the sending of signals. This interrupter is arranged in a manner to open the grid and plate circuits simultaneously, the generator circuits being established only when the sending of the 105 waves is desired. As a matter of fact this

has proved to be satisfactory by experience, and particularly in the case of tubes having a fine grid. In order to avoid possible disturbances, the grid circuit might be closed 5 after the closure of the plate circuit or the plate connection might be left in permanently closed condition, the manipulation being performed in the grid circuit. However, this last procedure has the inconvenience 10 that the generator is left under continuous tension. In reality it is sufficient that the grid and plate circuit are simultaneously closed. If this is done, each element performs its normal function and this will happen if the interrupter is situated in the manner shown in Fig. 3.

The source X which may obviously be an alternating current source in any of the arrangements according to my invention may 20 also be permanently connected with a resistance in order to avoid too high initial potentials in the plate-filament circuit when the interrupter is closed.

The connections between the antenna and 25 ground or the counterpoise may be reversed. That arrangement should be adopted which makes possible the elimination of the harmful capacity effects, and the interrupter may be connected in the antenna circuit.

In all cases the relation $\frac{L}{C}$ should have a 30 suitable value so that the maximum power of the generator may be developed in the antenna, the resistance of which acts in opposition. The two circuit arrangements, Figs. 2 and 3, are characterized by the fact that without any resort to couplings, the antenna is simply substituted in the place 35 of one of the elements constituting the system of capacities, inductances and resistances in which the waves would be locally generated. In other words, in place of utilizing a cathodic generator and an antenna connected with the generator circuit and 40 producing a new circuit in the local system, in accordance with the present invention, one of the elements already existing in the local system performs this service, whereby 45 the induction of a new element is obviated.

In the light of this definition, various arrangements different from those specifically described may be devised.

Although particularly described with reference to a transmitting system the invention 50 is also applicable to wireless telephone and telegraph receiving circuits with circuits similar to those described and with the addition of indicating circuits connected in various known ways.

It is advisable to adjust the regenerative condition so as to obtain the maximum sensitivity of the three-electrode audion tube used as a cathodic relay.

As above stated, identically the same apparatus as described for transmission may

be connected with receiving circuits, and the system will be put in an operative condition close to the adjustment where the valves start to generate oscillations.

In order to regulate the sensitiveness, the 70 heating of the filament or the potential between the grid and the filament is controlled.

The receiving circuit proper will extend 75 between any two points of the system thus constituted, e. g., between the grid and the filament of the generator. Any detector, but preferably an audion tube, may be used in this receiving circuit.

The two embodiments shown in Figs. 2 80 and 3 of the drawings are only for the purpose of illustrating the invention, and it should be understood that the various elements may be modified or resistances, 85 capacities, or inductances may be added to the circuits without departing from the spirit of the invention.

Having described my invention what I claim is:

1. In a radio signalling system, the combination of an antenna, a three electrode valve having a heated filament, a grid and a plate, a source of electromotive force between the plate and filament, an inductance between the plate and the filament, said inductance being also in the antenna, and an inductance connected to the grid and to said plate inductance, said plate inductance and antenna capacity being adapted to act 95 as an oscillation circuit common to the plate and antenna circuits, said oscillation circuit being the only physically tuned circuit in the system.

2. In a radio signalling system, the combination of a grounded antenna, a three 100 electrode valve having a heated grounded filament, a grid and a plate, a plate circuit containing a source of electromotive force and an inductance connected to the plate and the antenna at one end, to the grid at the 105 other end and to ground at an intermediate point by means of an adjustable connection.

3. In a radio signalling system, the combination of a grounded antenna, a three 110 electrode valve having a heated grounded filament, a grid and a plate, a plate circuit containing a source of electromotive force and an inductance connected to the plate and the antenna at one end, to the grid at the other end and to ground at an intermediate 115 point by means of an adjustable connection, and means for simultaneously interrupting the circuit between the filament and grid and between the filament and plate.

4. In a radio frequency arrangement, an 120 electron discharge device having an anode, cathode and control electrode, a tuned antenna circuit, means for regeneratively coupling the input and output circuits of said device together, and means for coupling 125 130

said device to said antenna circuit, whereby said antenna circuit is the only physically tuned circuit in the arrangement.

5. In a radio frequency arrangement, an electron discharge device having an anode, cathode and control electrode, a tuned antenna circuit, means for coupling the input and output circuits of said device together to produce oscillations, and means for coupling said device to said antenna circuit, whereby said antenna circuit is the only physically tuned circuit in the arrangement.

6. In a radio frequency arrangement, an electron discharge device having an anode, cathode and control electrode, a source of space current, a source of cathode heating current, one of said currents being alternating, a tuned antenna circuit, means for regeneratively coupling the input and output circuits of said device together, and means for coupling said device to said antenna circuit, whereby said antenna circuit is the only physically tuned circuit in the arrangement.

20 7. In a radio frequency arrangement, an electron discharge device having an anode, cathode and control electrode, a source of alternating space current, a tuned antenna circuit, means for regeneratively coupling

the input and output circuits of said device together, and means for coupling said device to said antenna circuit, whereby said antenna circuit is the only physically tuned circuit in the arrangement.

8. In a system of the class described, an electron discharge device having an anode, cathode and control electrode, an input circuit including said cathode and control electrode and an output circuit including said anode and said cathode, means for regeneratively coupling the input and output circuits of said devices, a third circuit responsive to the signal waves in said output circuit and a single adjustable device for said third circuit whereby said third circuit is the only physically tuned circuit in the arrangement.

9. In an electromagnetic wave transmitter employing an oscillatory valve, means for controlling the trains of oscillations comprising a permanent conductive connection between the control element of the valve and the negative lead of the high tension supply and a circuit interrupting device interposed in a conductor connecting the said negative lead and the filament of the valve.

MARIUS LATOUR.
